CLAIM

The ornamental design for a container with applicator tip and lid, as shown and described.

DESCRIPTION

FIG. 1 is a perspective view of a container with applicator tip and lid, shown with a partially enlarged section, showing my new design;

FIG. 2 is a bottom plan view thereof;

FIG. 3 is a side view thereof;

FIG. 4 is a front view thereof, and the back view being a mirror image thereof;

FIG. 5 is a top plan view thereof;

FIG. 6 is an exploded top plan view thereof;

FIG. 7 is a back view of the lid thereof, shown without the container for ease of illustration;

FIG. 8 is a side view of the container thereof, shown without the lid for ease of illustration; and,

FIG. 9 is a front view of the container thereof, shown without the lid for ease of illustration.

The broken line portions of FIG. 1 are included to show partly enlarged section only and form no part of the claimed design.

1 Claim, 4 Drawing Sheets
